EYEGLASSES.

1,008,240

Specification of Letters Patent.

Patented Nov. 7, 1911.

Application filed May 4, 1910. Serial No. 559,382.

To all whom it may concern:

Be it known that we, OSWALD B. CARSON and HARRY H. STYLL, both residing at Southbridge, in the county of Worcester and 5 State of Massachusetts, and citizens of the United States, have invented new and useful Improvements in Eyeglasses, of which the following is a specification.

Our invention relates to certain improvements in eyeglasses, and more particularly to that form of eyeglass in which there are employed spring actuated nose clips or guards, pivoted adjacent the opposite ends of the bridge; and the objects of our improvements are, first, to provide a spring that can be taken off and replaced without removing the pivot post; and second, to provide means for securely anchoring the free ends of said spring in a way to facilitate the 20 removing and replacing of the spring.

Another object of our invention is to provide a removable spring and at the same time retain the advantage of the usual retaining head or shoulder and the neat appearance of a spring snugly fitted to the pivot post.

We attain these objects by the construction illustrated in the accompanying drawing in which:

30 Figure 1 represents a rear elevation of an eyeglass embodying our invention. Fig. 2 represents a top or plan view of Fig. 1. Fig. 3 represents a plan section through the spring recess in lens strap. Fig. 4 represents a detail elevation of the pivot post. Fig. 5 shows a pivot post with a coiled spring being forced over its head. Fig. 6 shows a pivot post with a coiled spring being removed over the head.

40 Similar figures refer to similar parts through the several views.

Referring to the drawings: 1 designates a pivot post or stud, which is secured adjacent to the opposite ends of the bridge 2, and on which the guard or nose clip levers 3 are pivoted. 4 is a shoulder on said post 1, separating the guard lever 3 and the actuating spring 5, which is a coiled spring whose internal diameter is 45 substantially equal to the diameter of the shank 6 of the pivot post, and one end of

which is secured to the lever 3, while the other end is retained between the lens and the lens clip in the groove 7, which extends entirely across the inner face of the strap 55 8 of the lens clips, the grooves being formed by offsetting or pressing back the strap 8 from the edge of the lens. The head of the pivot post 1 tapers in both directions from a maximum diameter 9, the lower portion tapering from 9 to the shank 6, and the upper portion from 9 to a diameter 10, which is less than the internal diameter of the coiled spring 5.

The operation is as follows: The pivot 65 post 1 is secured in place with the lever 3 under the shoulder 4. One end of the spring 5 is pushed through the groove or opening 7, between the strap 8 and the lens, the internal diameter of the coil is then placed over the head at 10, and the spring pushed down, the tapering sides of the head acting as a wedge and forcing the spring to open out and slip over the maximum diameter of the head at 9. The spring is pushed down 75 onto the shank 6, which it snugly embraces, the free end is turned over and secured to the guard lever 3, and the end extending beyond the groove 7 is clipped off close to the strap or frame 8.

To remove the spring the operation is the reverse of that described above. The upper end of the spring is withdrawn from groove 7, the other end released from the lever 3, and the spring pulled up over the head, the 85 tapering portion of which, between shank 6 and the maximum diameter 9 acts as a wedge and opens up the coil, allowing its removal over the head.

It will be seen that by the use of our invention a broken or weakened spring can be quickly and cheaply replaced without injury to the mounting or the removal of the pivot screw, which removal, as is well known, usually strips the threads of the post or the bridge, making the threads worthless, and requiring the hole for the post to be reamed out, and a larger post fitted. It will also be noted that by the use of a groove or recess for the spring extending entirely through 95 the lens attaching means, springs of predetermined length are not required, the pro-

truding portion being cut off after the spring is in place; this facilitates the replacing of springs, and allows commercial or stock springs to be used with slight adjustment.

Having now described our invention, what we claim as new, and desire to secure by Letters Patent, is—

1. In eyeglasses provided with pivoted nose clamps, the combination of a coiled spring and a spring post having a head provided with downwardly and upwardly expanding tapered surfaces.

2. In eyeglasses provided with pivoted nose clamps, the combination of a spring post having a head provided with upwardly and downwardly expanding tapered surfaces; lens attaching means provided with a recess and a spring for actuating the nose clamps having one end inserted in said re-

cess and the other end held against the nose clamp.

3. In eyeglasses provided with pivoted nose clamps, the combination of a spring post provided with expanding means adapted to open the coil of the spring as it is placed thereon and removed therefrom, lens clips provided with means for holding the free end of the spring and a spring for actuating the nose clamps having one end held against the nose clamp and the other in the holding means on the lens clips.

In testimony whereof, we affix our signatures in the presence of two witnesses.

OSWALD B. CARSON.
HARRY H. STYLL.
